UNITED STATES PATENT OFFICE.

ERNST SCHUCHARD, OF BERLIN-FRIEDENAU, GERMANY.

JIGGING-MACHINE.

1,118,239.

Specification of Letters Patent.

Patented Nov. 24, 1914.

Application filed November 18, 1913. Serial No. 801,740.

To all whom it may concern:

Be it known that I, ERNST SCHUCHARD, engineer, a subject of the German Emperor, residing at 1 Süd-West-Corso, Berlin-Friedenau, Germany, have invented new and useful Improvements in Jigging-Machines, of which the following is a specification.

In the known methods of separating material in jigging machines, where the supply of the new material takes place at the surface of the material, which forms in the several settling compartments of the jigging machine comparatively high layers, it is necessary that the heavier grains, the separation of which forms the object of the process, should gradually work through their way on to the sieve or the deeper parts of the whole layer, where they come to rest and are finally discharged. It is clear that the resistance, which has to be overcome by the grains in order to reach the positions, from which they may be discharged, is very considerable. It is also obvious, that very considerable time is required for the heavy grains to pass through a comparatively high layer of material. These circumstances are the chief reason, why the jigging machines at present in use have to be made of a very considerable length, or why a comparatively large number of such compartments have to be placed in one row and used in succession in order to obtain a satisfactory separation. Moreover, the action of the jigging water upon the new material supplied from above upon the thick layer of material is considerably weakened owing to the fact that the water has to pass through the whole thickness or height of the layer placed upon the carrier before it reaches the new supply.

It is the object of the present invention to obviate these drawbacks of the known jigging machines. With this object in view the carrier is provided at the point of supply with an elevated portion, upon which the material to be separated is subjected in the form of a thin layer to the direct action of the jigging water. From this elevated portion, the products of the jigging operation pass over an adjacent inclined or step-shaped portion of the carrier directly to the points of discharge. The material is thus subjected at the supply end of the jigging machine to the full action of the jigging water, the separation of the material into heavier and lighter particles being ef-

fected very rapidly, almost instantaneously. The heavier particles of the material need not, therefore, work through a comparatively high layer of the material, but it is only required, that the particles should be transported or allowed to slide toward the discharge apparatus in the relative positions, which they have assumed at the entry into the jigging machine under the full action of the water. Owing to this arrangement, the length of the various jigging compartments may be considerably shortened and the total number of the compartments may be reduced. This considerable shortening of the jigging compartments enables several compartments to be acted upon by a common jigging piston, whereby a great economy in the initial cost of the plant and in the working expenses may be obtained.

Several constructions of the invention are shown in the drawings by way of example.

Figures 1 and 2 are sectional elevations of two constructions and Figs. 3 and 4 are the corresponding cross sections. Figs. 5, 6, 7 and 9 are sectional elevations of several modifications, Fig. 8 shows a modification of the carrier.

The jigging machine shown in Fig. 1 consists of a single jigging compartment or sieve *a*. The supply of the material takes place from the funnel *b* upon the elevated portion of the settling carrier *c* which is subdivided into sections by vertically or slightly inclined non-perforated partitions *d*. The carrier may be composed of several parts or it may be made in one piece, the parts *d* being in the latter case non-perforated. The settling carrier is inclined downwardly from the point of supply toward the discharge devices *e*.

The jigging machine shown in Fig. 2 consists of a single jigging compartment or sieve *f*. The supply of the material takes place from the funnel *g* upon the elevated portion of the settling carrier *h*, which is subdivided into sections by vertically or slightly inclined non-perforated partitions *i*. The carrier may be composed of several parts or it may be made in one piece, the parts *i* being in the latter case non-perforated. The settling carrier is inclined downwardly from the point of supply toward the discharge devices *k*.

In the construction shown in Fig. 1, the part extending from the elevated portion to

the discharge device in step-shaped, while in the construction shown in Fig. 2 the said part is downwardly inclined but straight.

The jigging machine may of course be provided with any desired number of perforations or sieves.

In the constructions shown in Figs. 5 to 8 several troughs or grooves serving for the discharge of the divers separated materials 10 and arranged directly side by side are used in connection with a single operative portion of the jigging sieve, a different product being obtained in each groove or trough. The main advantage obtained by this arrangement is a further considerable reduction of 15 the length of the machine. Moreover, as the transport of the finished products to the discharge troughs or grooves takes place along the shortest possible path and without 20 any interruption, the efficiency of the machine is greatly increased.

In the construction shown in Fig. 5 the operative portion of the jigging sieve or carrier adjacent to the point of supply is designated by the letter *m*; the several discharge 25 grooves *n* are joined directly to this portion and are arranged side by side extending in the same direction.

In the modification shown in Fig. 6, the 30 operative portion *l* of the carrier or sieve is corrugated and forms steps descending toward the discharge groove *o*.

The carrier shown in Fig. 7 differs from that shown in Fig. 6 in that the bottoms of 35 the discharge grooves *p* are arranged along a descending line.

In the construction shown in Fig. 8, a portion *t* of the operative part of the carrier or sieve is formed flat.

40 In the construction shown in Fig. 9 has the elevated portion of the carrier or sieve downwardly inclined toward the portion, which serves for the discharge. The jigging machine shown in Fig. 9 consists of one jigging compartment 1. The material is supplied on to the elevated portion 2 of the sieve or carrier, which is inclined toward the portion 3 of the carrier, serving for the discharge of the various materials.

50 Claims.

1. A jigging machine comprising a water receptacle, a means for supplying material, a stationary perforated grooved carrier for supporting the materials to be separated, 55 mounted over said receptacle, said carrier

having an elevated portion at the point of supply an adjacent inclined portion and discharge grooves formed therein, and means for establishing a pulsating current of water through the carrier, substantially as described. 60

2. A jigging machine comprising a water receptacle, a means for supplying material, a stationary perforated grooved carrier for supporting the materials to be separated 65 mounted over said receptacle, said carrier having an elevated portion at the point of supply an adjacent inclined portion and discharge grooves formed therein, said grooves arranged side by side and increasing in 70 width with the increase of their distance from the point of supply, and means for establishing a pulsating current of water through the carrier, substantially as described. 75

3. A jigging machine comprising a water receptacle, a means for supplying material, a stationary perforated grooved carrier for supporting the materials to be separated mounted over said receptacle, said carrier 80 having an elevated portion at the point of supply, an adjacent inclined portion and discharge grooves formed therein, said grooves arranged side by side and descending on a line from the point of supply, and means for 85 establishing a pulsating current of water through the carrier, substantially as described.

4. A jigging machine comprising a water receptacle, a means for supplying material, 90 a stationary perforated grooved carrier for supporting the materials to be separated mounted over said receptacle, said carrier having an elevated portion at the point of supply, an adjacent inclined portion and 95 discharge grooves formed therein, said grooves arranged side by side and having partitions, increasing in height with the increase in the distance of the grooves from the point of supply, and means for establishing a pulsating current of water through 100 the carrier, substantially as described.

In testimony whereof I have signed my name to this specification in the presence of two subscribing witnesses.

ERNST SCHUCHARD.
